DISPLAY DEVICE

Filed July 23, 1925

2 Sheets-Sheet 2

UNITED STATES PATENT OFFICE.

EDWIN C. ESSINGER, OF CHICAGO, ILLINOIS.

DISPLAY DEVICE.

Application filed July 23, 1925. Serial No. 45,640.

To all whom it may concern:

Be it known that I, EDWIN C. ESSINGER, a citizen of the United States, residing at Chicago, in the county of Cook and State of Illinois, have invented certain new and useful Improvements in Display Devices, of which the following is a specification, reference being had to the accompanying drawings.

10 This invention relates to certain improvements in display devices and it is an object of the invention to provide a device of this kind adapted for use in connection with the original container of a commodity, such as candy, and which when in applied position provides means for making an effective display of the commodity within the container without hindering or obstructing the access to said container when it is desired to dispense the contents thereof.

15 It is also an object of the invention to provide a device of this general character which, when not in use, may be readily compacted to occupy a minimum of space and to facilitate shipment.

20 Another object of the invention is to provide a device of this kind provided with a holder for a price card or the like adapted to overlie the outer face of a wall of the original container.

25 The invention consists in the details of construction and in the combination and arrangement of the several parts of my improved display device whereby certain important advantages are attained and the device rendered simpler, less expensive and otherwise more convenient and advantageous for use, as will be hereinafter more fully set forth.

30 The novel features of my invention will hereinafter be definitely claimed.

35 In order that my invention may be the better understood, I will now proceed to describe the same with reference to the accompanying drawings, wherein:—

40 Figure 1 is a view in perspective of a display device constructed in accordance with an embodiment of my invention and 45 in applied position;

50 Figure 2 is a view in perspective of my improved device as herein disclosed unapplied;

55 Figure 3 is a fragmentary detailed sec-

tional view taken substantially on the line 3—3 of Figure 2;

60 Figure 4 is a longitudinal vertical sectional view taken through the structure as illustrated in Figure 1;

65 Figure 5 is a view in plan of my improved device compacted or folded;

70 Figure 6 is a view in perspective of the cover frame as herein employed.

75 As disclosed in the accompanying drawings, my improved device comprises a body plate 1 of desired dimensions and preferably rectangular and having hingedly connected to its side marginal portions the inclined marginal portions of the side plates 2 so that when the plates 2 are in extended or supporting position the body plate 1 will be disposed on a desired downward incline.

80 The hinged connection between each of the side plates 2 and the body plate 1 comprises a series of intermeshing knuckles 3 extending slightly beyond the adjacent edges of said plates 1 and 2 and through which knuckles 3 is directed a suitable pintle rod or member 4. By this means, each of the side plates 2 when swung in one direction is permitted to overlie a face of the plate 1 but prevented from passing when moved in the opposite direction beyond a vertical center or a plane substantially at right angles to the plate 1.

85 The plates 2 are of a length substantially equal to the length of the original container C with which the device is adapted to be employed and the plate 1 is of a width substantially equal to the width of such original container. The forward or low end of each of the plates 2 is of a height less than that of an end flange 5 of the original container C while the rear or high end of each of the plates 2 is of a height considerably in excess of the opposite end flange of the container C, said height, however, being determined by the angle on which the plate 1 is disposed when supported by the plates 2.

90 The rear end of the plate 1 is formed thereacross with a bead 6 to reinforce said plate 1 and also to prevent injury by contact with said rear end portion of the plate 1.

95 The forward end portion of the plate 1 has pivotally connected therewith through

the medium of the coating knuckles 7 and pintle rod 8, a relatively narrow plate 9 extending substantially entirely thereacross, while the opposite or outer marginal portion 5 of such plate 9 has pivotally connected thereto through the medium of the coating knuckles 10 and pintle rod 11 a flat plate 12. This plate 12 is provided with suitable means, as at 14, to retain a price card or the 10 like.

When my improved display device is in use, the side plates 2 are extended into operative or working position and positioned within the original container immediately 15 adjacent to the side flanges 15 thereof with the narrow plate 9 upwardly disposed and in close contact with the forward end flange 5 of the original container. When so arranged, the outer marginal portion of this 20 plate 9 extends upwardly above the adjacent end flange 5 of the container C to permit the flat plate 12 to be readily swung downwardly to a position to overlie the outer face of said end flange so that the price card 16 will 25 be effectively exposed.

After the improved device has been mounted or arranged as just described, a suitable tray T is superimposed upon the plate 1, said tray being packed to display the character 30 of the contents of the container C, such as chocolates or the like. By this means, the purchaser may readily determine the character of the commodity or goods within the container C and ready access 35 may be had within said container for the dispensing of its contents through the opening provided by the upper raised or extended portion of the device.

Should the original container and the 40 applied display device and tray be mounted exteriorly of a showcase or other exposed location, the tray T may have disposed thereover a protecting glass cover 17 carried by the frame 18 adapted to be slipped upon the 45 side walls 19 of the tray T. If the assembly is arranged within a showcase or the like, the use of this protecting cover may be dispensed with.

When the device is not in use the side 50 plates 2 may be readily swung to overlie the plate 1 and each other and when so arranged the flat plate 12 is swung inwardly to overlie the adjacent ends of said folded or compacted plates 2 and the plate 1 whereby the 55 adjacent corners of the plates 2 are shielded.

When folded or compacted my improved device constitutes a relatively small package which may be readily mailed or otherwise shipped and which occupies but a minimum 60 of space when stored away for further use.

It is also to be noted that the side plates 2 are relatively thin. This is of advantage when the device is being employed in connection with containers having candy or the 65 like as its contents as said side plates may be

readily inserted or applied within the container without injury to such contents.

From the foregoing description it is thought to be obvious that a display device constructed in accordance with my invention is particularly well adapted for use by reason of the convenience and facility with which it may be assembled and operated, and it will also be obvious that my invention is susceptible of some change and modification 70 without departing from the principles and spirit thereof and for this reason I do not wish to be understood as limiting myself to the precise arrangement and formation of the several parts herein shown in carrying 75 out my invention in practice except as hereinafter claimed.

I claim:—

1. In combination with a container, a display device comprising side plates insertable within the container, the upper margins of said plates being inclined, the low point of each of the plates terminating within the container and the high point exteriorly thereof, a body plate, means for operatively connecting the inclined marginal portions of the side plates to the body plate, a plate pivotally connected with the low end of the body plate and upwardly disposed when the device is applied, and a flat plate pivotally connected with the opposite marginal portion of said last named plate. 80

2. A display device comprising, in combination, side plates, each having an inclined margin, a body plate, means for pivotally connecting the inclined marginal portions of the side plates to the body plate, said side plates when moved in one direction overlying the body plate, a plate pivotally connected with the end portion of the body plate adjacent to the low ends of the inclined edges of the side plates, and a flat plate pivotally connected with the last named plate, said side plates when folded to overlie the body plate partially overlying the third named plate, the flat plate being movable to overlie the adjacent end portions of said folded side plates. 100

3. A display device comprising, in combination, side plates, a body plate, means for pivotally connecting the side plates to opposite marginal portions of the body plate, a plate pivotally connected with an end portion of the body plate, and an additional plate pivotally connected with the outer marginal portion of the last named plate. 115

4. A display device comprising, in combination, side plates, a body plate, means for pivotally connecting the side plates to opposite marginal portions of the body plate, a plate pivotally connected with an end portion of the body plate, and an additional plate pivotally connected with the outer marginal portion of the last named plate. 125

• plate, both of said two last named plates being of a length substantially co-extensive to the width of the body plate.

5. A display device comprising, in combination, side plates, a body plate, means for pivotally connecting the side plates to opposite marginal portions of the body plate, a plate pivotally connected with an end portion of the body plate, and an additional plate pivotally connected with the

outer marginal portion of the last named plate, the means for pivotally connecting the side plates to the body plate preventing each of said side plates when swung in one direction passing beyond a plane substantially at right angles to the body plate.

15 In testimony whereof I hereunto affix my signature.

EDWIN C. ESSINGER.
